(57) **CLAIM**

The ornamental design for a spout for portable fuel container, as shown and described.

DESCRIPTION

FIG. 1 is a perspective view of a spout for portable fuel container showing my/our new design;

FIG. 2 is another perspective view thereof;

FIG. 3 is a right side view thereof;

FIG. 4 is a left side view thereof;

FIG. 5 is a front elevational view thereof;

FIG. 6 is a rear elevational view thereof;

FIG. 7 is a top plan view thereof; and,

FIG. 8 is a bottom plan view thereof.

The broken line showing of a spout for a portable fuel container is included for the purpose of illustrating portions of the article and forms no part of the claimed design.

1 Claim, 8 Drawing Sheets
